Primary Examiner — Cynthia M. Chin

(57) **CLAIM**

The ornamental design for a set of toy building block, as shown and described.

DESCRIPTION

FIG. 1 is a front perspective view of a set of toy building block, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded view thereof;

FIG. 10 is an enlarged detail view of area 10 in FIG. 1; and,

FIG. 11 is an enlarged detail view of area 11 in FIG. 2.

The broken lines are included to show enlarged partial views in FIGS. 1, 2, 10 and 11 and form no part of the claimed design.

1 Claim, 11 Drawing Sheets
